(57) **CLAIM**

The ornamental design for a child stroller seat, as shown and described.

DESCRIPTION

FIG. 1 illustrates a perspective front view of a child stroller seat;

FIG. 2 illustrates a front view of the child stroller seat;

FIG. 3 illustrates a back view of the child stroller seat;

FIG. 4 illustrates a side view of the child stroller seat;

FIG. 5 illustrates a top view of the child stroller seat;

FIG. 6 illustrates a bottom view of the child stroller seat;

FIG. 7 illustrates a side view of the child stroller seat docked with a stroller.

FIG. 8 illustrates a perspective front view of a second embodiment of a child stroller seat;

FIG. 9 illustrates a front view of the second embodiment of the child stroller seat;

FIG. 10 illustrates a back view of the second embodiment of the child stroller seat;

FIG. 11 illustrates a side view of the second embodiment of the child stroller seat;

FIG. 12 illustrates a top view of the second embodiment of the child stroller seat; and,

FIG. 13 illustrates a bottom view of the second embodiment of the child stroller seat.

The broken or dotted line illustration of the stroller, sunshade, stitching, and product marking are for illustrative purposes of the environment of the child stroller seat and form no part of the claimed design.
